FRANK BROWN, OF LOS ANGELES, CALIFORNIA.

LETTERING-GUIDE.

1,262,744.

Specification of Letters Patent. Patented Apr. 16, 1918.

Application filed August 28, 1916. Serial No. 117,358.

To all whom it may concern:

Be it known that I, FRANK BROWN, a citizen of the United States, residing at Los Angeles, in the county of Los Angeles 5 and State of California, have invented new and useful Improvements in Lettering-Guides, of which the following is a specification.

My invention relates to a lettering guide. 10 It is an object of my invention to provide a simple device providing longitudinal openings of varying width, which constitute guides for applying letterings and the like to architectural drawings, and the 15 like.

My device consists of a transparent body plate, preferably provided with guiding means such as guide lines at right angles to each other enabling the operator to position 20 the lettering guide in relation to the figures on the drawings. On the main plate, a peripheral flange is mounted whose lower face is in a plane slightly above the plane of the lower face of the main plate. The inner 25 sides of the flange are cut away to form with the adjacent sides of the main plate, a series of longitudinal openings constituting lettering guides.

In one of the forms of the lettering guide, 30 the flange is adjustably connected to the main plate whereby the width of the longitudinal opening may be regulated as desired. The flange is provided with graduations adapted to register with a stationary mark, 35 whereby the width of the opening may be measured.

In the accompanying drawings which form a part of this specification, I have illustrated two forms of my device, and in 40 which:

Figure 1 is a top plan view of my lettering guide.

Fig. 2 is a side elevation thereof.

Fig. 3 is a vertical section taken on line 45 3—3, Fig. 1.

Fig. 4 is a top plan view of a modification of the invention.

Fig. 5 is a section taken on line 5—5, of Fig. 4.

Referring to Figs. 1, 2 and 3, the lettering guide consists of a rectangular flat bottom plate 10 with a beveled edge. A plate 11 50 of the same shape but larger is cemented on the bottom plate 10 and forms a marginal flange 11' of uniform width extending laterally therefrom on the four sides. On the

inner side of the flange 11', a plurality of longitudinal guide openings 12 are provided which I have shown as four in number, one for each side of the flange 11'. These openings are of various widths to accommodate letters or figures of different sizes. The guide openings 12 are arranged parallel to the sides of the bottom plate as shown in Fig. 1. The outer edges of the openings 60 65 are formed by the flange 11', while the inner edges are formed by the edges of the bottom plate 10. The outer longitudinal edges of the guide openings are beveled and inclined toward the beveled edges of the bottom plate 10. In order to bring the work nearer to the draftsman, I prefer to cut recesses 13 in the top plate, extending from the beveled edge of the bottom plate 10 for a slight distance, and parallel thereto. I have 70 75 shown the lettering guide illustrated in Figs. 1, 2 and 3 as composed of two plates cemented together, though it will be understood that the same may be formed of one piece. 80

The lower face of the bottom plate 10 is provided with parallel lines 14 at right angles to each other, which constitute guide lines and assist the draftsman in properly positioning his lettering guide on the drawings in relation to lines or figures thereon. 85

Referring to the modification shown in Figs. 4 and 5, the same consists of a bottom plate 15, rectangular in shape, and provided on its lower face with two sets of parallel 90 guide lines 16 at right angles to each other. Marginal flanges 17, are either formed integral with said bottom plate 15 or are securely cemented to the corners thereof and extend from three sides. The inner sides 95 of said flanges 17 are recessed as at 18, forming with the edges of the bottom plate 15 longitudinal guide openings 19 with parallel straight edges, said edges being beveled. On the fourth side of the bottom plate 15 and between the outer ends of the first and third flanges 17 is an adjustable guide flange 20. The legs 21 of the adjustable flange are provided with slots 22 through which threaded bolts 23 secured to the bottom plate 105 15 extend. Milled thumb nuts 24 engage said bolts and serve to clamp the adjustable flange 20 in position. The inner side of the adjustable flange is beveled and forms with the beveled edge of the main plate 15 an 110 adjustable lettering guide. The outer edges of the legs 21 are provided with graduations

- 25 adapted to register with indicia such as arrow heads 26 on the adjacent sides of the fixed flanges 17, whereby the width of the slot may be measured. 27 indicate apertures 5 passing through the main plate whereby the lettering guide may be conveniently suspended from a nail or pin.

In the operation of the lettering guide, the same is placed on the drawing and moved 10 in position, the guide lines on the face of the bottom plate assisting the draftsman to place it in the position desired in relation to the figures of the drawings. Then with 15 a drawing pen, or the like, the letters are written in the guide opening that has been selected for use. The height of the letters is determined by the width of the guide opening, and the draftsman is enabled to apply letters of uniform height with ease 20 and rapidity, the opposite edges of the opening acting as stops to the movement of the pen. Since the marginal flange of the lettering guide is spaced from the bottom face of the bottom plate, the lettering device 25 may be moved in the direction of the major axis of the guide opening which is in use, without danger of blurring the wet ink of the lettering.

In using the modification shown in Figs. 30 4 and 5, the width of the lettering guide opening formed by the adjustable flange 20 may be regulated as described.

I prefer to construct the bottom plate and the marginal flanges of celluloid, but any 25 other suitable transparent material may be substituted therefor.

The marginal flanges may be provided 40 with spacing lines 28 which extend parallel to the letter guide openings. By means of these spacing lines the draftsman is enabled to space the lines of his letterings by moving the lettering guide toward him so that the spacing line will register with the top or 45 bottom of the lines just completed. The inner edge of the letter guide opening may be provided with graduations 29 to assist the draftsman in horizontally spacing the individual letters or digits.

It will be understood by those skilled in 50 the art that various changes in the detail of the construction and arrangement of the parts may be made without departing from the spirit of my invention as defined by the appended claims.

55 I claim:

1. A lettering guide comprising a flat polygonal central body plate of transparent material, guide flanges laterally extending from each side of said plate, said flanges 60 lying in a plane slightly above the plane in which said plate is positioned, and having cut away portions each forming with the adjacent side of said plate a longitudinal letter guide opening, the long edges of said 65 opening being beveled, said plate being pro-

vided with guide lines at right angles to each other whereby the lettering guide may be positioned on the paper in relation to the drawings thereon.

2. A lettering guide comprising a rectangular main body plate of transparent material adapted to lie flat on the paper to be lettered, and provided with guide lines whereby the same may be positioned on the paper in relation to the drawings thereon, 70 marginal flanges secured to said plate, and extending from three sides, the lower faces of said flanges being slightly above the lower face of said main plate, the inner edges of said flanges being cut away to form 75 with the adjacent sides of said plate a series of letter guide openings of different width, an adjustable flange mounted on the fourth side of said plate and having legs provided with slots, a pair of threaded bolts secured 80 to said plate and extending through said slots, thumb nuts on said bolts for clamping said adjustable flange in position, whereby the same may be adjusted to form with the adjacent edge of said plate a longitudinal 85 letter guide opening of variable width, the long edges of all of said guide openings being beveled.

3. A lettering guide comprising a main body plate, adapted to lie flat on the paper 90 to be lettered, an adjustable guide flange mounted thereon, said guide flange extending laterally from said plate and slightly above the lower face of said main plate, means for adjustably clamping said guide 100 flange to said main plate, said means comprising a pair of threaded bolts secured to said main plate and extending through slots in said guide flange, and thumb nuts on said bolts, the inner edge of said flange forming 105 with the adjacent edge of said main plate a longitudinal letter guide opening of variable width, said guide flange being provided with indicia for measuring the width of said opening.

4. A lettering guide comprising a main body plate made of transparent material adapted to lie flat on the paper to be lettered, and a guide flange laterally extending from one side thereof, said guide flange 115 forming with the adjacent edge of the main body plate a letter guide opening, said plate being provided with guide lines whereby the lettering guide may be positioned on the paper in relation to the drawings thereon.

5. A lettering guide comprising a main body plate made of transparent material adapted to lie flat on the paper to be lettered, said plate being provided with means for positioning the same in relation to the 125 drawings on the paper on which it is to be used, an adjustable guide flange extending laterally from one of the sides of said main plate, the inner side of said flange forming with the adjacent side of said plate a letter 130

guide opening of variable width, and means for adjustably holding said guide flange in relation to said main plate, said flange being provided with indicia for measuring the width of said letter guide opening.

6. A lettering guide, comprising a main body plate of transparent material adapted to lie flat on the paper to be lettered, and an adjustable guide flange extending laterally from one side of said main plate, the inner edge of said flange forming with the adjacent edge of said main plate a longitudinal lettering opening of variable width, the lower face of said guide flange being elevated to permit the movement of the device in the direction at right angles to the length of said opening without touching the letters formed in said letter guide opening.

7. A lettering guide comprising a main body plate made of transparent material adapted to lie flat on the paper to be lettered, said plate being provided with means for positioning the same in relation to the drawings on the paper on which it is to be used, a guide flange extending laterally from one of the sides of said main plate, the inner side of said flange forming with the adjacent side of said plate a letter guide opening, said flange being laterally movable in

relation to said plate and provided with indicia for measuring the width of said lettering guide opening, and means for holding said flange in adjusted position, the side of said plate forming said opening being provided with a scale for spacing the letters to be formed in said opening.

8. A lettering guide comprising a main body plate adapted to lie flat on the paper to be lettered, a guide flange extending laterally from one side of said plate, and said guide flange being made of transparent material, said flange being slightly above the bottom face of said plate and the inner side of said flange forming with the adjacent side of said plate a longitudinal letter guide opening, and means on said plate for positioning the same in relation to the drawing of the paper on which it is to be used, one of the edges forming said opening being provided with indicia for laterally spacing the letters formed in said opening, said flange being provided with indicia for spacing the lines of letters formed in said opening.

In testimony whereof I have signed my name to this specification.

FRANK BROWN.
